ECCENTRIC TYPE STEEL PLATE LIFTING CLAMP

Joseph C. Renfroe, Jacksonville, Fla.

Application July 10, 1944, Serial No. 544,244

5 Claims. (Cl. 294—104)

My invention relates to improvements in steel plate lifting clamps, and more particularly to a plate lifting clamp of the eccentric type in which a pivoted plate clamping jaw is moved into clamping engagement with a steel plate on which the clamp is placed when a pull is put on the lifting cable attached to an eye in the outer end of the eccentric head or shackle attached to the clamp body.

An object of my invention is to provide an improved steel plate lifting clamp which will be provided with a plate receiving slot and a swivel jaw and pivoted jaw mounted at the opposite sides of the slot, said pivoted clamping jaw being brought into automatic operation by means of an eccentric head member and interconnected cam links, when a pull is exerted on the lifting cable attached to an eye in the free end or outer end of the said shackle or eccentric head member.

Another object of my invention is to provide an improved eccentric type steel plate lifting clamp, which will include a slotted body adapted to support a swivel jaw and a pivoted jaw at the opposite sides of said slot, said body being further provided with a centrally disposed upwardly extending guide head formed with an elongated bearing slot in alignment with the hereinbefore mentioned slot in the clamp body, and a split eccentric shackle mounted on said guide head upon a pin movable in the slot in the guide head, together with a pair of interconnecting cam links operatively connected between the ends of said pin and the free or outer end of the pivoted clamping jaw, whereby any lift on the shackle will cause an immediate and positive action of the clamping jaw upon a steel plate upon which the clamp is positioned.

A still further object of my invention is to provide an improved eccentric type cam operated steel plate lifting clamp which will provide an eccentric power gripping effect on the immediate lift of the clamp shackle, said clamp being highly efficient in operation and relatively inexpensive to manufacture.

Other objects will appear as the description proceeds.

In the accompanying drawings which form a part of my application,

Figure 1 is a perspective view of my improved eccentric type steel plate lifting clamp showing a steel plate in clamped position within the slot in the clamp between the fixed jaw and the pivoted jaw, and

Figure 2 is a vertical sectional view taken through the body of the clamp showing the piv-

oted jaw member in retracted or unclamped position.

Like characters of reference are used throughout the following specification and the accompanying drawings to designate corresponding parts.

In carrying out my invention I provide an improved automatically operated eccentric type steel plate lifting clamp having a body 1 formed with a plate receiving slot 2 in its lower edge, and a centrally disposed upwardly extending guide head 3 formed with an elongated bearing slot 4 arranged in alignment with the said plate receiving slot 2 in the body 1. A fixed or swivel jaw 5 will be received in one face of the plate receiving slot 2 in the body 1, the same being held in place by means of the pin 6, and the opposite side of the slot 2 will be formed by the spaced depending legs 7, between which the bearing pin 8 is mounted to support the pivoted steel plate clamping jaw 9, the plate engaging portion of the clamping jaw being provided with the toothed surface 10.

From the drawings, it will be apparent that 25 spaced bearing surfaces 11 will be formed on the body 1 at the base of and at the opposite sides of the upwardly extending guide head 3 formed integrally with the body 1. A split shackle 12 formed with an eye 13 in its outer end and with 30 the oppositely extending eccentrics or cams 14 and 15 on its lower end will be operatively supported over the guide head 3, upon the bearing pin 15' adapted to extend between the leg portions of the split shackle and through the elongated slot 4 in the guide head 3. The cam connecting links 16 will be connected between the outer ends of the bearing pin 15' and the outer end of the pivoted plate clamping jaw 9, whereby 35 a rocking movement of the shackle 12 in either direction will cause the cam 14 or 15 to rock along the bearing surfaces 11 with a consequent immediate pull on the cam connecting links 16, which in turn will pull the plate clamping jaw 9 into engagement with a plate in the clamp. A 40 lifting cable with hook 17 will be connected to a suitable hoist (not shown), the said hook being adapted to hook into the eye 13 in the split shackle 12.

From the foregoing description, it will be apparent that in actual use, a workman will place a clamp on the opposite ends of a large steel plate, and as soon as the hoist begins to exert a pull on the lifting cable and on the shackle, the eccentric or camming action of the rockable cam shackle will cause the immediate action

or gripping of the pivoted plate clamping jaws upon the steel plate, and the clamps will remain on the plate as long as there is any lift on the shackle. Furthermore, it will be seen that the action of the clamp will be immediate and positive regardless of the position of the clamp or pull of the lifting cable attached to the shackle, due to the arrangement and construction of the split shackle with its oppositely extending cams.

It will be apparent that many minor changes in detail of construction may be resorted to without departure from the spirit of the invention.

Having thus described my invention what I claim as new and desire to secure by Letters Patent of the United States is:

1. An eccentric type steel plate lifting clamp formed with a plate receiving slot in one edge thereof, a fixed jaw and a pivoted jaw mounted in the opposite sides of said slot, a guide head formed integrally with the clamp body and formed with an elongated bearing slot in alignment with the slot in the edge of the clamp body, a shackle adjustably supported in the slot in said guide head formed with cam surfaces adapted to engage and rock on bearing surfaces on the clamp body at the opposite sides of the guide head, and cam connecting links between said shackle and said pivoted jaw.

2. An eccentric type steel plate lifting clamp formed with a plate receiving slot in one edge thereof, a fixed jaw and a pivoted jaw mounted in the opposite sides of said slot, an adjustable shackle having cam surfaces mounted on the clamp body and having a rocking engagement

therewith, and cam links connected between said shackle and pivoted jaw whereby movement of the shackle will cause the operation of the pivoted jaw to engage a steel plate when in the slot in the clamp body.

3. A steel plate lifting clamp formed with a plate receiving slot in one edge thereof, said clamp body being formed with a bearing slot in alignment with said first mentioned slot, a fixed jaw and a pivoted jaw mounted in the opposite sides of said plate receiving slot, a shackle rockably supported in the bearing slot in the clamp body formed with cam surfaces and links connecting said pivoted jaw and shackle for causing the actuation of the pivoted jaw upon movement of the shackle with respect to the clamp body.

4. A steel plate lifting clamp including a body having a fixed jaw and a pivoted jaw, spaced bearing surfaces formed on the clamp body, a shackle carried by the clamp body formed with cam surfaces adapted to ride on the said bearing surfaces, and links connecting said pivoted jaw and shackle for causing the pivoted jaw to function.

5. A steel plate lifting clamp including a body having a fixed jaw and a pivoted jaw, spaced bearing surfaces formed on the clamp body, a shackle slidably mounted on the clamp body and formed with oppositely disposed cams for riding on the bearing surfaces, and links connecting said pivoted jaw and shackle for causing the pivoted jaw to engage a steel plate when in position within the clamp.

JOSEPH C. RENFROE.
